UNITED STATES PATENT OFFICE.

CHARLES E. SCRIBNER, OF CHICAGO, ILLINOIS.

TELEPHONE-EXCHANGE SYSTEM.

SPECIFICATION forming part of Letters Patent No. 391,762, dated October 23, 1888.

Application filed June 6, 1881. Serial No. 35,037. (No model.)

To all whom it may concern:

Be it known that I, CHARLES E. SCRIBNER, a citizen of the United States, residing at Chicago, in the county of Cook and State of Illinois, have invented a certain new and useful Improvement in Telephone-Exchange Systems, (Case 27,) of which the following is a full, clear, concise, and exact description, reference being had to the accompanying drawings, forming a part of this specification.

My invention relates to that system of telephone-exchange in which the subscribers' telephone-lines are grouped or connected through a common line at the central office, in which is placed a telephone. The operator stands listening at this telephone, and is thus always ready to answer a subscriber. The subscriber has only to take down his telephone and speak directly into his transmitter. The subscribers soon learn not to interfere with one another, since each can hear the conversation that is going on between the operator and any other subscriber.

Heretofore the common wire has been grounded at the central office, and the outer ends of the wires have been connected to a common line, as will be seen by reference to my patent, No. 266,321, granted October 24, 1882, for telephone-exchange system, application filed March 22, 1881. Where, say, twenty-five telephone-lines are thus connected to a common ground-wire at the central office, it is evident that if, for example, four subscribers should have their telephones down and should be in connection with the listening operator there would be five ground-connections—one at the central office and one at each of the four subscribers' stations. Therefore the voice-current sent from any one of those stations would be divided and pass to ground in derived circuit at four other ground points. The number of subscribers, therefore, which may be advantageously included in a single group is limited. If, however, the common wire at the central office, instead of passing to ground, is connected with a second group of telephone-lines, it is evident that when two subscribers of opposite groups take down their telephones a closed circuit will be formed from their grounds through the listening operator's telephone, included in the common wire at the central office, and thus the voice-current

sent from either subscriber's station through the common wire will not be weakened by reason of a ground being formed at the station 55 of any subscriber of the opposite group. On the other hand, in case all the telephones of one group are hung up so that there is no ground-connection with said group telephonic communication may be maintained between 60 any subscriber of the other group and the listening operator, since the first group, when disconnected from the ground, acts as one plate of a condenser.

My invention consists in the method of operating telephone-exchanges, whereby the condenser capacity of two groups thus connected to the opposite ends of a common wire is taken advantage of to enable any subscriber of one group to communicate with the listening operator having his telephone included in said common wire.

My invention also consists in grouping the subscribers' lines on opposing sides of the wire containing the listening operator's telephone 75 outfit, and thereby dispensing with the ground-connection at the central office.

My invention is illustrated in the accompanying drawings, in which—

Figure 1 is a diagram illustrative of my invention. Fig. 2 is a view of the same somewhat in detail.

Like parts are indicated by similar letters of reference throughout the different figures.

Referring now to Fig. 1, it will be seen that there are two groups of telephone-lines connected with the same switch-board at the central office and thence to a common line, including the operator's telephone *g*. The telephone-lines of the stations 1, 2, 3, and 4 constitute group A, and the telephone-lines of stations 5, 6, 7, and 8 constitute group B. There may be in practice, say, from twenty to twenty-five lines in each group. At station 8 I have shown a subscriber's outfit consisting of telephone *a*, switch *b*, and bell *c*. Any other subscriber's outfit may be used at the different subscribers' stations. The outer ends of the telephone-lines of group A are connected with the common line *d*, while the outer ends of the telephone-lines of group B are connected by the common line *f*. There are normally no ground-connections except when the subscribers remove their telephones from the switches.

When a telephone is thus removed from a switch, as shown at station 8, the telephone-line *e* will be disconnected from the bell *c* and the common line *f* and closed to ground, as shown through the switch *b* at said station. The subscriber on thus taking down his telephone may speak at once to the operator listening at telephone *g*, the condenser capacity of group A being sufficient to allow the voice-current sent from station 8 to operate the telephone *g*, although there may be no ground whatsoever upon group A. Suppose subscriber 8 asks for subscriber 2. The operator, on being informed of the connection desired, by inserting plug *h* in switch 2 sends current from the negative pole of battery *i* over line *k*, through bell *l* at station 2. The current, after passing through said bell, finds circuit back to the positive pole of the battery by common line *d*, and such telephone-lines of group A as happen at the time to be connected with said common line. The current after passing through said bell *l*, being distributed through several different telephone-lines, will not be strong enough in any one line to ring the bell included therein. As described in my said patent, the bells may be polarized, if desired, so as to respond to current in but one direction. Subscriber 2 will thus be notified by the ringing of his bell and will at once take down his telephone from the switch, and thereupon the switch will automatically assume the position shown at station 2 in Fig. 2. Line *k* will thus be disconnected from the common line *d* and closed to ground through the telephone at station 2, as shown. The plug *h* is then removed and subscribers 8 and 2 may then be connected together by a flexible cord provided with terminal plugs, as shown upon the switch-board at the central office in Fig. 2. Any two subscribers, whether of the same or opposite groups, may thus be connected together. Lines when thus in use are cut off from the listening operator's telephone. A clearing-out drop may be included in the circuit of the connecting-cord in the usual manner. Lines in use, therefore, are thus insulated from the other lines of the system. If, however, several subscribers take down their telephones at the same time to speak to the listening operator, there will be a ground-connection established at each station of the subscribers who are thus asking for connection; but as the lines are distributed in groups on different sides of the telephone *g* it will in practice never happen that so many lines of one group will be grounded as to interfere with the successful working of the system.

Having thus described my invention, I claim as new and desire to secure by Letters Patent—

1. In a telephone exchange system, the combination, with two groups of telephone-lines, of a telephone placed in a line between said groups, a common line connecting the outer ends of each of said groups, and switching apparatus at the different subscribers' stations, whereby any telephone-line may be discon-

nected from the outer line of its group and connected to ground to form a circuit through the telephone at the central office.

2. In a telephone-exchange, the combination, with two groups of telephone-lines, each group being normally connected with a different outer common line, of a telephone outfit at the central office included in a line connecting said groups and switching apparatus and telephones at the different subscribers' stations, whereby any telephone-line may be closed to ground at the subscriber's station located thereon and telephonic communication established between the subscriber at said station and the operator at the central office.

3. The combination, with a group of telephone-lines disconnected from the ground, of a telephone-line connected with said group through a telephone at the central office and through a subscriber's telephone outfit at the subscriber's station on the line, whereby telephonic communication may be maintained between the subscriber's said station and the central office.

4. A telephone-circuit including two telephones located at different stations, one end of said circuit being connected with the ground and extending from said ground through both of the telephones, the portion of said circuit beyond said telephones being disconnected from the ground, but of sufficient extent to act as one plate of a condenser, whereby communication may be maintained between the said telephones.

5. In a telephone-exchange system, the combination, with two groups of telephone-lines connected at the central office on different sides with the same telephone, of outer common lines, one for each group, said outer common lines being disconnected from the ground, bells at the different subscribers' stations, one in each telephone-line, and a battery and switching apparatus at the central office, whereby current may be sent out over any one of said telephone-lines to ring the bell at the station on said line.

6. Telephone-lines radiating at the central office from the different sides of a telephone to subscribers' stations, the telephone-lines on each side of the central-office telephone being normally connected with a common line and disconnected from ground, and a subscriber's telephone outfit at each station, whereby any subscriber may disconnect from the common outer line and close his line to ground by the act of removing his telephone from its support to speak with the listening operator.

7. In a telephone-exchange, telephone-lines radiating from the central office to different subscribers' stations, a switch-board at the central office provided with switches, one for each telephone-line, a wire at the central office including a listening operator's telephone, the telephone-lines after passing through their respective switches being connected in groups on different sides of said operator's telephone, the different groups of wires being connected

at their outer ends with a common line, a subscriber's telephone outfit at each of the subscribers' stations and switching apparatus at the central office, whereby any two telephone-lines may be connected together and insulated from the other telephone-lines of the system.

8. The telephone at the central office in a loop between two groups of telephone-lines, several of the lines of each group being 10 grounded at the subscribers' stations thereon, whereby any of said several subscribers may communicate with the listening operator.

9. The combination, with telephone-lines radiating from a central office to subscribers' 15 stations and provided with subscribers' telephone outfits at the different stations, of a telephone included in a loop connecting the two groups of said lines, whereby any subscriber in either group may communicate with the operator at said telephone.

10. The combination, with a telephone and telephone-lines connected with opposite sides of said telephone, the said telephone-lines ex-

tending to subscribers' stations and being provided at the different subscribers' stations with 25 a telephone, telephone-switch, and a bell, of a battery and switching apparatus at the central station, whereby signals may be sent from the central station to any subscriber's station, substantially as described.

11. A telephone included in a loop at the central station, the opposite ends of said loop being connected each with a different group of telephone-lines, each subscriber's line being provided with a telephone in a ground-circuit 35 and a switch, whereby any subscriber may close his line through his telephone to ground and communicate with the operator at the telephone in the loop, the telephone-lines of the different groups when not in use serving 40 as condensers.
